SLIDE FASTENER CONSTRUCTION

Howard J. Murphy, Lynnfield, Mass., assignor to
 United-Carr Fastener Corporation, Cambridge,
 Mass., a corporation of Massachusetts

Application February 16, 1946, Serial No. 648,143

5 Claims. (Cl. 24—205.11)

1

The present invention relates to slide fastener constructions and aims generally to improve constructions of slide fasteners and the like.

One of the objects of the invention is the provision of an improved terminal end for coil type slide fasteners in which the end provides an anchor for the coil end.

A further object of the invention is the provision of an improved separable end stop for slide fasteners.

The above and other objects of the invention will be apparent to persons skilled in the art from a consideration of the accompanying drawings and annexed specification illustrating and describing one preferred embodiment of the invention.

In the drawings:

Fig. 1 is a detail perspective view of a fragmentary portion of a pair of slide fastener stringers, the end stops being shown separated;

Fig. 2 is a front elevation of a fragmentary portion of a slide fastener showing the end stops connected;

Fig. 3 is a horizontal sectional view through the joined end stops as taken on the line 3—3 of Fig. 2;

Fig. 4 is a vertical sectional view of the female end stop attached to a slide fastener stringer shown in elevation;

Fig. 5 is a transverse sectional view of the female end stop as taken on the line 5—5 of Fig. 4;

Fig. 6 is an enlarged perspective view of the disassembled parts of the female end stop according to the illustrated embodiment of the invention;

Fig. 7 is a front elevation of the male terminal end; and

Fig. 8 is a vertical central sectional view of the male terminal stop.

Referring to the drawings, the improved slide fastener construction comprises a pair of opposed stringers or tapes 9, 10 to the meeting edges of which are secured the fastener elements, herein shown as consisting of helical coils 11—12 of non-circular ribbons adapted to interlock in meshing engagement when the fastener is closed by means of a slider, not shown.

The stringers or tapes 9 and 10 are preferably woven or otherwise constructed to a flanged cross section, preferably T-shaped, to provide lateral flanges 9^a—10^a on one or both sides of the web 9^b—10^b of the stringers 9 and 10, respectively. The coils are suitably secured to the face of the flanges 9^a and 10^a by suitable means,

2

as for example by weaving the tapes to the successive convolutions of the coils as disclosed in my copending application Serial No. 579,746, filed February 26, 1945 now matured into Patent Number 2,504,078 dated April 11, 1950.

According to the invention, means are provided to secure the terminal ends of the coils to the stringer so as to hold the coil securely in place relative to the stringer edge to relieve strain on the threads attaching the successive coil convolutions to the stringer tapes. Such means may be embodied in a separable end stop for the fastener, permitting the fastener to be separated as desired after the slider has been moved to the bottom of the fastener, as is the case where the fastener is used as a closure for garments, such as coats, jackets, sweaters and the like. In the embodiment selected for illustration in the drawings, the invention may be embodied in male and female members 15 and 16, respectively, for this purpose.

The male member or terminal end 15 for the stringers preferably comprises an elongated sleeve having a relatively flat body portion 17, an integral end portion 18 and inturned side flanges 19 spaced from and parallel to the body 17 (see Figs. 7 and 8). The body 17 is preferably of a width to overlie the two flanges 9^a or 10^a of a stringer and the end portion 18 preferably abuts the end of the stringer. The member 15 is securely attached to the stringer by crimping the inturned flanges 19 against the opposite face of the stringer flanges 9^a—10^a, thus encompassing the end of the stringer flanges on all sides. Preferably the end 11^a—12^a of the coils 11—12 are extended into the end stops and gripped between the body 17 and flanges 19. Or as illustrated in Figs. 7 and 8, the end 12^a of the coil may be formed as an eye or loop to receive a lug 17^a on the upper edge of the front wall 17 of the male member 15 and thus anchor the end of the coil to the member 15. Thus the members 15 provide an anchoring socket for the terminal ends of the coils serving to relieve strain on the threads attaching the successive coil convolutions to the stringer flanges.

In the illustrated embodiment of the invention the male member may be, and preferably is constructed as above described, and as illustrated in Figs. 7 and 8.

The female member 16 which may form a bottom stop may be and preferably is similarly formed with a body 20 and inturned flanges 21 to embrace opposite sides and edges of the stringer to which it is attached as well as the

terminal end of the coil, such as the coil end 11a as shown in Figs. 5 and 6. The female member 18 is further formed with a socket or cup 24 formed integrally with or attached to the stop 16 to receive the male member 15, and is of such dimensions that it forms a stop for the slider as will be understood.

As herein disclosed the female member 18 may be formed at its terminal end with oppositely disposed laterally extending flanges 22 and 23 projecting respectively from the body 20 and the flange 21 as illustrated in Figs. 4 and 6, adapted to be embraced by the cup or socket member 24 whereby the latter may be securely attached to the member 16.

The cup or socket 24 may be suitably formed to receive and be attached to the member 16 while providing a laterally projecting recess 25 for the reception of the male member 15. One desirable construction of cup or receptacle 24 is illustrated in the drawings, and comprises a member having an intermediate base portion 26 and angularly disposed opposed channeled sides, the latter having a web portion 27 and inturned edge flanges 28. Such a cup or receptacle may be simply and economically formed from a channel shaped strip, the flanges of which are cut from an intermediate portion throughout a length slightly greater than the width of the body 16 and flange 20. The cup 24 may be folded as shown in Fig. 6 and then slipped over the terminal end of the stop 16 so that the base 26 of the cup 24 underlies one of the flanges 22-23 and the inturned flanges 28 overlie at least one of the flanges 22 and 23. As illustrated, the base 26 of the cup 24 underlies the flange 22 of the stop 16 and the flanges 28 of the cup overlie the flange 23 of the stop 16. Thus the socket or cup 24 is securely attached and locked to the stop body 16 and is prevented from longitudinal displacement thereon.

The width of the flanges 22-23 of the female end stop 16 is such as to maintain the adjacent edges of the flanges 28 of the sides 27 in spaced-apart relation to provide guides 29 for the passage of the stringer webs 9b and 10b as is illustrated in Fig. 3, thus avoiding the necessity of extending the end stop 15 and 16 below the end of its stringer 10.

The members 15 and 16 will ordinarily be securely attached to the stringers against displacement therefrom by clamping action of the compressed or clinched body and opposed edge flanges 17-19 and 20-21. If desired, additional locking means may be provided in the form of a tongue 30 cut from the metal of the end stop, for example, the body 17 or 20, and pressed inwardly into biting engagement with the associated stringer.

Advantages of the invention reside in the simplicity of construction as well as of application of the component parts of the separable end stop to the stringer. The provision of a terminal end member having a body and spaced opposed flanges permits the members to be readily applied to a coil-attached stringer with the body overlying one face of the stringer and terminal end of the coil and the edge flanges 19 and 21 bearing against an opposite face of the stringer, so that compression of the body and flanges together securely binds the stringer end and coil end together. Furthermore, the provision of a socket or cup 24 of the type illustrated and described on the female end stop permits the ready interlocking of the adjacent stringer ends.

Although I have illustrated and described a single preferred embodiment of the invention, I do not intend to be limited thereto as the scope of the invention is best defined in the appended claims.

I claim:

1. A slide fastener construction comprising: a pair of stringer tapes, each having a web portion and opposed laterally extending flanges along a longitudinal edge of the web portion; a fastener coil secured to each tape along said longitudinal edge with the convolutions of the coil secured to the flanges of the tape, said coil having a terminal end extending angularly to the end convolution of the coil and positioned adjacent the flanges of said tape; an end stop member at the end of each tape comprising a substantially flat plate portion and wing portions extending from opposing side edges of said flat plate portion in substantially parallel relationship to said plate portion, said plate portion and said wing portions being in gripping engagement with opposing faces of the flanges of the tape with the terminal end of the coil in secured gripped engagement between said plate portion and said wings; one of said end stop members having opposed end flanges extending normal to the plate portion and the wing portions thereof; and a socket member comprising an elongated sheet metal body bent to provide a U-shaped longitudinal cross-section with a base and opposing leg portions, each of said leg portions having opposed wing flanges extending normal thereto from opposite side edges toward the flanges of the other leg portion, said socket member being assembled to said one of said end stop members with a side edge of a wing flange of each leg portion spaced from the base of said body for receiving an end flange of said one end stop member and securing it to the base of said socket member and with the other wing flanges of said leg portions in engagement with the end edge of the other end flange of said one end stop member thereby positioning said one end stop member within said socket member to provide a socket between said other wing flanges and said one end stop member whereby the other end stop member may be received therebetween with the web portion of the tape attached to said other end stop member extending between said other wing flanges.

2. In a slide fastener assembly, an end stop construction comprising a stringer tape having a web portion and a flange of flexible sheet material extending angularly from a longitudinal edge of the web portion, an end stop member secured to one end of said tape having a plate portion in engagement with one face of the flange and a wing portion extending from one side edge of said plate portion in engagement with an opposite face of said flange, opposed flanges extending from the end of said end stop member at the end of said tape, and a socket member of sheet material secured to said end stop member comprising opposing leg portions connected by a base portion, a wing extending from the edge of one leg portion toward the other leg portion and having a side edge spaced from said base portion and said side edge of said wing being in engagement with an end flange of said end stop member, and a second wing extending from an edge of a leg portion on a side opposite that of said first mentioned wing and engaging an end of the other end flange of said end stop member and being spaced thereby from

said end stop member to provide a socket for receiving a cooperating end stop member on the end of a cooperating stringer tape.

3. In a slide fastener construction, an end stop construction comprising a stringer tape having a web portion and opposed flanges of flexible sheet material extending angularly from a longitudinal edge of the web portion, an end stop member secured to one end of said tape having a plate portion in engagement with the faces of said flanges opposite the web portion and wing portions extending from opposite side edges of said plate portion in engagement respectively with the faces of said flange adjacent the web portion, opposed flanges extending from the end of said end stop member at the end of said tape, and a socket member of sheet material secured to said end stop member comprising opposing leg portions connected by a base portion, wings extending from the side edges of said leg portions toward each other, the wings on one side of said socket member having side edges spaced from said base portion securing to said base portion one end flange of said end stop member, and the wings on the other side being disposed in engagement with the end of the other end flange of said end stop member and spaced thereby from said end stop member to provide a socket for receiving a cooperating end stop member on the end of a cooperating stringer tape.

4. An end stop construction in accordance with

claim 3 having a slide fastener coil secured to the flanged longitudinal edge of the stringer tape with each convolution of the coil being secured to the flanges.

5. An end stop construction in accordance with claim 3 having a slide fastener coil secured to the flanged longitudinal edge of the stringer tape with each convolution of the coil secured to the flanges and provided with a terminal end angularly disposed to the end convolution of the coil and in secured engagement between the plate portion of the end stop member and the wing portions of the end stop member.
